CLAIM

The ornamental design for animal feeder, substantially as shown and described.

DESCRIPTION

FIG. 1 is an isometric view of an animal feeder, showing my new design;

FIG. 2 is a top plan view thereof;

FIG. 3 is an elevational view taken from one side thereof, the opposite side being the same as the side shown;

FIG. 4 is a front elevational view thereof, the rear being the same as the front shown; and

FIG. 5 is a bottom plan view thereof.
